Primary Examiner — Susan Bennett Hattan*Assistant Examiner* — Omeed Agilee(74) *Attorney, Agent, or Firm* — AdamsIP, LLC; Edward B Garner, III; James H Adams(57) **CLAIM**

The ornamental design for a rehabilitation support, as shown and described.

DESCRIPTION

FIG. 1 is a front elevated perspective view of a rehabilitation support showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a rehabilitation support showing the claimed design in a folded position such that it may be used as a support.

The broken lines in the drawings depict portions of the rehabilitation support that form no part of the claimed design.
